Carol Kennedy S.

UNITED STATES PATENT OFFICE.

DANIEL M. PIFER, OF SULLIVAN, ILLINOIS, ASSIGNOR OF ONE-THIRD TO HOMER C. SHIREY, OF SULLIVAN, ILLINOIS.

BROOM.

Application filed April 10, 1925. Serial No. 22,160.

This invention relates to improvements in brooms and has for an object the provision of novel means for removably attaching a handle to the head of a broom, so that the head may be renewed when desired.

Another object of the invention is the provision of means for housing or enclosing the handle attaching means and thus add to the strength and appearance of the broom. 10 With the above and other objects in view, the invention further includes the following novel features and details of construction, to be hereinafter more fully described, illustrated in the accompanying drawings and 15 pointed out in the appended claims.

In the drawings:—

Figure 1 is an elevation of a portion of a broom constructed in accordance with the invention.

20 Figure 2 is a sectional view taken substantially on the line 2—2 of Figure 1.

Figure 3 is a fragmentary elevation showing the means for attaching the handle.

Referring to the drawings in detail where- 25 in like characters of reference denote cor- responding parts, the broom head which is indicated at 10 has removably attached thereto a handle 11. This handle may be in the form of the usual wooden handle, or 30 of any other type.

The handle 11 may be removably secured to the broom head and for this purpose the latter has extending therefrom a core 14 which is embedded within the head and 35 which extends outwardly for a short dis- tance. The broom fibers are secured around the core by suitable binding 15 and are con- fined by means of a band 16. This band is longitudinally corrugated as shown at 17 40 with the corrugations biting into the broom fibers so as to securely hold them in place. These corrugations further provide rein- forcement for the band 16 which is relatively wide and may be made of thin sheet metal. 45 The edges of the band are preferably rolled or reinforced as indicated at 18.

Secured to the extended end of the core 14 by suitable securing means such as is in- 50 dicated at 19 is a tubular member 20, the said member extending beyond the end of the core and providing a socket for the re-

ception of the movable handle. The handle is detachably secured within the socket by means of screws or equivalent fastening de- 55 vices 21.

Surrounding the tubular member 20 and extending over the upper portion of the broom head is an apron 22. This apron is provided at one end with a relatively thick knurled portion 23 and has a threaded en- 60 gagement with the adjacent end of the tubular member as indicated at 24. The apron is flared towards its opposite end so as to en- 65 gage over the binding means 15 of the broom head and as this apron encloses the tubular member and the fastening devices 21, it, in addition to providing a finish for the broom acts to reinforce the joint between the handle and broom head and serves to prevent acci- 70 dental removal of the fastening devices 21. 70

The invention is susceptible of various changes in its form, proportions and minor details of construction and the right is herein reserved to make such changes as properly fall within the scope of the appended claims. 75

Having described the invention what is claimed is:—

1. In a broom, the combination with a head having a core extending therefrom, a tubular member extending from and secured to the core, means for securing one end of a handle within the tubular member, an apron removably positioned over the tubular mem- 80 ber and upper portion of the head and en- closing the handle securing means and means to hold the apron in position.

2. In a broom, the combination with a head having a core extending therefrom, a tubular member secured to and extending from the core to define a socket, a handle having one end positioned within the socket, fasten- 90 ing devices extending through the tubular member into the handle to removably hold the device in place, and an apron extending around the tubular member over the fasten- 95 ing devices to prevent accidental removal of the latter, said apron having one of its ends threadedly engaging the adjacent end of the tubular member and providing a removable reinforcing housing. 100

In testimony whereof I affix my signature.

DANIEL M. PIFER.
